[57] **CLAIM**

The ornamental design for the improved Christmas tree stand, as shown and described.

DESCRIPTION

FIG. 1 is an isometric view of a Christmas tree stand showing my new design;

FIG. 2 is an enlarged top plan view thereof the legs partially broken away for ease of illustration;

FIG. 3 is a reduced bottom plan view thereof; and,

FIG. 4 is an isometric view of a second embodiment of FIG. 1, the difference residing in the removal of the water level indicator.

FIG. 1

FIG. 2

FIG. 3

FIG. 4
